Primary Examiner — Robert M Spear*Assistant Examiner* — Darcey E Heflin(74) *Attorney, Agent, or Firm* — Warner Norcross and Judd LLP(57) **CLAIM**

The ornamental design for a portion of container, as shown and described.

DESCRIPTION

FIG. 1 is a perspective view of a portion of container; FIG. 2 is an enlarged perspective view of a portion of container;

FIG. 3 is a left side view thereof;

FIG. 4 is a right side view thereof;

FIG. 5 is a front view thereof;

FIG. 6 is a rear view thereof;

FIG. 7 is a top view thereof; and,

FIG. 8 is a bottom view thereof.

FIGS. 1-8 show portions in broken lines. The broken line portions are shown for environmental purposes and form no part of the claimed design. The broken line segments immediately adjacent the solid line portions of the design define the boundary of the design, but do not themselves form part of the claimed design.
